[57] CLAIM

The ornamental design for a table water fountain, as shown and described.

DESCRIPTION

FIG. 1 is a perspective view of the present invention; FIG. 2 is a front view of the FIG. 1 embodiment, the rear view being a mirror image thereof; FIG. 3 is a left side view of the embodiment in FIG. 2; FIG. 4 is a right side view of the embodiment shown in FIG. 2; FIG. 5 is a top view of the embodiment shown in FIG. 2; FIG. 6 is a bottom view of the embodiment of FIG. 2; FIG. 7 is a perspective view of an alternate embodiment thereof with the only difference being in the proportion; FIG. 8 is a front view thereof; FIG. 9 is a perspective view of a further alternate embodiment thereof with the only difference being in the proportion; and, FIG. 10 is a front view thereof.

The broken line showing in FIGS. 1 and 7 is for illustrative purposes only and forms no part of the claimed design.
